UNITED STATES PATENT OFFICE.

HARRISON H. EATON, OF BEVERLY, MASSACHUSETTS.

PIPE CUTTER.

Application filed July 8, 1922. Serial No. 573,579.

To all whom it may concern:

Be it known that I, HARRISON H. EATON, a citizen of the United States of America, and resident of Beverly, in the county of 5 Essex and State of Massachusetts, have invented new and useful Improvements in Pipe Cutters, of which the following is a specification.

This invention relates to hand operated 10 implements for cutting pipe and more particularly to devices of the general type disclosed in the patent to Eaton, No. 1,162,905, Dec. 7, 1915.

The principal objects of the present invention are to provide an improved device 15 of the above type capable of performing the cutting operation rapidly, and to this end so constructed and arranged that the depth of cut is at least as great at the end of the 20 operation as at the beginning; to provide a device capable of severing a pipe without undue exertion on the part of the user even though the outer surface of the work be rough or eccentric; and having provision for 25 removing such burr as may be formed upon the interior of the pipe during the cutting operation.

In the accompanying drawings there is 30 shown by way of example, a preferred embodiment of the device of the present invention, and in such drawings:—

Fig. 1 is a rear elevation of a pipe cutter constructed according to the present invention, certain portions being broken away; 35 Fig. 2 is a front elevation of the cutter device, certain parts being broken away, the cutter and depth gage being indicated in the relative positions which they occupy substantially at the beginning of the operation; 40 Fig. 3 is a view similar to Fig. 2 but showing the cutter and depth gage at a later stage of the operation; and

Fig. 4 is a fragmentary edge view showing details of a reamer device associated 45 with the cutter.

Referring to the drawings, numerals 1, 2 indicate respectively work-clamping jaws pivotally connected at the point 3. The 50 jaw 1 is furnished with angularly disposed work-engaging surfaces 4, 5, while the jaw 2 is furnished with similar surfaces 6, 7, the several surfaces being of sufficient length to prevent twisting of the pipe clamped therebetween. A piece of pipe is 55 indicated at 8 as secured between the engaging surfaces of the jaws.

A handle member 9 is pivotally secured at the point 10 to the jaw 2, such handle having a laterally extending arm 11. The outer end of the jaw 2 is provided with spaced 60 ears 12, 13, between which is positioned the end of a connecting link 14 pivotally secured to such ears by means of a pin 15. This link 14 is screw threaded for a substantial portion of its length, as indicated at 16, and such threaded portion normally engages a slot 17 formed in one end of a resilient plate 18 secured to the outer surface of the jaw 1 by means of a screw 19. A nut 20 has screw threaded engagement with the link 16, 65 such nut having a rim 21 constituting a hand wheel whereby the nut may be turned. Preferably the slotted outer end of the plate 18 is bent slightly as shown at 22 in order to prevent the nut 20 from slipping 70 therefrom. The link 16 and the nut 20 as thus arranged serve releasably to secure the jaws 1 and 2 in operative position.

The arm 11 of the handle member is furnished with a shallow groove or slot in its 75 front face, such groove having the substantially parallel side walls 23, 24 and the oblique end wall 25 conveniently formed by securing a filler piece 25^a in the lower end of the slot. This groove serves for the reception of a cutter 26 of trapezoidal form, made with an opening 26^a for the reception of a screw 26^b whereby it may be secured in position. The cutter is provided with cutting edges 27, 28 at its opposite 80 ends, one of such cutting edges projecting beyond the arm 11 and the other seating in the angle between faces 23 and 25.

A second shallow slot or groove 29 is also formed in the front face of the arm 11, such slot having the parallel side walls 30, 31 respectively and constituting a guideway for a movable depth gage 32. This depth gage is furnished with a work-engaging face 33 and with a lateral slot providing an edge 34 which normally engages a cam surface 35 formed upon a rotary shaft 36. This cam surface comprises a concentric portion and an eccentric portion 37, alternatively engageable with the edge 34. The shaft 36 is provided with a mutilated pinion 38 at the rear of the arm 11, such pinion meshing with a gear segment 39 secured to the jaw 2. The shaft is retained in operative position by means of a cotter pin 40 extending through an opening in such shaft and bearing against the forward surface of a cover 100 105 110

plate 41 secured by means of screws such as 42 against the forward surface of the arm 11 and serving to retain the depth gage 32 in operative position in its guideway. A conical reamer 43 is secured by means of a bolt 44 at any convenient point upon the handle 9. Preferably, the arm 11 is scooped out at 45 at a point between the cutter 26 and the depth gage 32 to provide a bevelled surface 10 for deflecting the chip from the plane of the cut. The depth gage is also provided with a similar chip guiding surface at 46 in its forward face.

In the operation of the device, the pipe 8 is clamped between the jaws 1 and 2 in the manner above described, the handle 9 being swung in a counterclockwise direction as viewed in Fig. 2 to permit the insertion of the pipe between the jaws. When the handle 20 occupies such position, the sector 39, acting upon the gear 38, serves to position the shaft 36 substantially as indicated in Fig. 2, wherein the edge 34 of the depth gage rests upon the concentric portion of the cam 25 surface. The depth gage as thus positioned serves to determine the depth to which the cutting edge 27 of the cutter may be forced into the pipe. The operator now seizes the handle 9 and swings the entire device in a 30 clockwise direction about the axis of the pipe, thus carrying the cutter circumferentially about the pipe and removing a chip of predetermined thickness therefrom. When the cutter has made a complete revolution 35 about the pipe, the depth gage then enters the groove formed by the cutter, thus permitting the cutter to move inwardly toward the center of the pipe for removing another chip. It is evident that the handle 40 9 will swing slightly about its pivot point 10 as the gage moves radially into the pipe, but as the gage is at a greater distance from the pivotal point 10 than the cutter, the gage will tend to approach the axis of the pipe 45 more rapidly than does the cutting edge of the cutter. Such action would constantly tend to decrease the depth of cut as the cutting operation progressed and in order to avoid this action, applicant has provided the 50 cam arrangement above described for positioning the depth gage. As the handle 9 swings about its axis 10, the segment 39, engaging the pinion 38, turns the shaft 36 so that the eccentric portion 37 of the cam is 55 brought into engagement with the edge 34 of the gage. As the gage and cutter swing toward the work along arcs having different radii (that of the gage being the longer) the gage tends to approach the center of the 60 work more rapidly than the cutter so that if they were relatively fixed the normal differences in the distances of the cutter and gage from the center of the work would quickly decrease and the depth of cut would likewise diminish. By suitably calculating the 65

cam surface 37 the gage is allowed to recede gradually relatively to the cutter so as exactly to compensate for the effect of their different distances from the axis 10 and thus the depth of cut is kept substantially uniform throughout the operation. Under some circumstances it may be found desirable to form the cam surface 37 of such contour as to permit the gage to move outwardly at a greater rate than above described, thus progressively increasing the depth of cut as the diameter of the pipe decreases. 70

As the plate 18 is somewhat resilient, the jaws 1 and 2 may spring apart slightly during the rotation of the cutting implement 80 about the axis of the pipe, such action being highly desirable in view of the fact that pipe is frequently eccentric and has a rough surface, so that with jaws rigidly clamped together it would be very difficult, if not impossible, to swing the implement about the pipe. 85

While the type of cutter herein employed usually produces but little burr, it is found that in some instances a slight burr may be 90 formed upon the interior of the pipe and for removing this burr the reamer device 43 is provided, such device being conveniently arranged upon the handle 9 so that the handle may be employed in rotating the reamer for 95 removing the burr from the interior of the pipe.

What I claim and desire to secure by Letters Patent of the United States is:

1. A pipe cutter comprising work clamping means, a cutter, a depth gage, and means for automatically varying the position of the cutter and gage relatively to each other during the cutting operation. 100

2. A pipe cutter comprising work clamping jaws, a cutter, a depth gage, means for pressing said cutter and gage against the work, and means permitting the depth gage to move relatively to the cutter during the cutting operation. 105

3. A pipe cutter comprising work clamping means, a pivotally mounted handle member, a cutter fixed to said handle member, a depth gage movably supported upon said handle member, and means for automatically causing the gage to retract as the cutting operation progresses. 110

4. A pipe cutter comprising work holding means, a pivoted member having a cutter mounted thereon, a depth gage also carried by said pivoted member, said gage and cutter being at different distances from the pivotal axis of said member, and means for automatically permitting the gage to retract relatively to the cutter as the cutting operation progresses. 120

5. A pipe cutter comprising work holding means, a pivoted member having a cutter and depth gage mounted thereon, the cutter being arranged nearer the pivotal axis of 130

said member than the gage and having its cutting edge nearer the center of the work, in a radial direction, than the work engaging element of the gage, and means for automatically maintaining such difference in radial distance as the cutting operation progresses.

6. A pipe cutter comprising work holding means, a pivoted member, a cutter and a 10 depth gage mounted upon said member, the cutter being nearer the pivotal axis of said member than the gage, and means operable during the cutting operation for compensating for the greater arcuate movement of the 15 gage about said axis whereby to prevent decrease in the depth of cut during the cutting operation.

7. A pipe cutter comprising means for holding the work, a pivoted handle member, 20 a normally fixed cutter secured to said member, a depth gage mounted upon said member and arranged to slide in a direction substantially radial of the work, said gage being at a greater distance from the pivotal axis 25 of said member than the cutter, and means permitting said gage to move relatively to said handle member as the latter is actuated to move the cutter over the surface of the work.

30 8. A pipe cutter comprising work holding means, a pivoted member having a cutter mounted thereon, a depth gage slidable in a guideway in said member, cam means for determining the operative position of the 35 gage relatively to the cutter, and means for actuating such cam means in accordance with the movement of said pivoted member for insuring a uniform depth of cut during the entire cutting operation.

40 9. A pipe cutting implement having work clamping means, a pivoted handle member, a cutter secured to the handle member, a depth gage mounted in a guideway in said handle member, a rotary shaft journaled in 45 said handle member and having a cam element engaging the gage for determining the position of the latter relatively to the cutter, a pinion fast to said shaft, and a relatively fixed gear sector meshing with said pinion 50 for causing the latter to turn as the handle member is actuated.

10. A pipe cutting implement comprising pivotally connected, work clamping jaws, a handle member fulcrumed to one of said 55 jaws, a cutter secured to said handle member, a depth gage slidable in a guideway in said member, said gage being at a greater distance from the pivotal axis of the handle member than the cutter, a rotary cam 60 bearing against said gage for determining its position relative to that of the cutter, a gear sector fixed to the jaw upon which the handle member is fulcrumed, and a pinion

meshing with said sector and transmitting motion to said cam as the handle is actuated 65 whereby to permit the gage progressively to retreat along its guideway.

11. An implement of the class described comprising a pair of jaws, a handle pivoted to one of said jaws, a cutter secured to said 70 handle, and means, comprising a resilient plate fixed to one jaw, for connecting the free ends of said jaws the resiliency of the plate permitting slight relative movement of said jaws. 75

12. A cutting implement of the class described comprising a pair of jaws pivoted together, a cutting element supported by one of said jaws, and means comprising a resilient plate secured to one jaw for connecting the free ends of said jaws during the operation of the cutting element the resiliency of the plate permitting slight relative movement of the jaws. 80

13. A cutting implement of the class described comprising a pair of jaws pivoted together, a cutter supported upon one of said jaws, a link secured to the free extremity of one of said jaws, and a resilient plate fixed to the other jaw and having a 85 slot for the reception of the link whereby to retain the jaws in operative relationship. 90

14. An implement of the class described comprising a pair of pivoted jaws, a cutter supported by one of said jaws, a link having 95 pivotal connection with the free extremity of one of said jaws, said link having an externally screw threaded portion and a nut engaging the same, and a resilient member secured to the other jaw and having a 100 slot in its extremity for the reception of the link and a surface with which the nut may engage whereby to hold the jaws in operative relationship. 100

15. A pipe cutter comprising a pair of 105 pipe engaging jaws pivoted together, a handle pivotally secured to one of said jaws, said handle having a recess provided with parallel side walls and an end wall oblique with respect to such side walls, a double 110 ended cutter lodged in said recess with one of its ends bearing against said oblique wall, and a cover member for retaining the cutter in operative position. 115

16. In combination with a handle member, a cutter fixedly mounted upon the handle member, work clamping means pivotally secured to the handle member, a depth gage movably mounted upon the handle member, and means controlled by variations in relative position of the handle and clamping means for automatically retracting the gage as the cutting operation progresses. 120

Signed by me at Boston, Massachusetts, this fifth day of July, 1922.

HARRISON H. EATON.
